UNITED STATES PATENT OFFICE

160,937

ADVERTISING CABINET

Leonard H. Goldman, Phoenix, Ariz.

Application August 22, 1949, Serial No. 4,636

Term of patent 7 years

(Cl. D1—11)

To all whom it may concern:

Be it known that I, Leonard H. Goldman, a citizen of the United States, residing at 46 North 1st Street, Phoenix, State of Arizona, have invented a new, original, and ornamental Design for an Advertising Cabinet, of which the following is a specification, reference being had to the accompanying drawing, forming a part hereof.

I claim:

The ornamental design for an advertising cabinet, as shown.

LEONARD H. GOLDMAN.
